UNITED STATES PATENT OFFICE

111,660

DESIGN FOR A GAME DEVICE

Ruth Bowman Mott, Tampa, Fla.

Application July 12, 1938, Serial No. 78,425

Term of patent 3½ years

To all whom it may concern:

Be it known that I, Ruth Bowman Mott, a citizen of the United States, residing at Tampa, in the county of Hillsborough and State of Florida, have invented a new, original, and ornamental Design for a Game Device, of which the following is a specification, reference being had to the accompanying drawing, forming part thereof.

I claim:

The ornamental design for a game device, as shown.

RUTH BOWMAN MOTTO.
